United States Patent

Des. 236,852
Patented Sept. 16, 1975

236,852

FILM CARTRIDGE

Carter Keith Reh, Santa Ana, and Cyril E. Fankhouser III,
Costa Mesa, Calif., assignors to United Visuals Corporation,
Los Angeles, Calif.

Filed Oct. 26, 1973, Ser. No. 410,183

Term of patent 14 years

Int. Cl. D16—05

U.S. Cl. D61—1 T

FIG. 1.

FIG. 2.

FIG. 3.

FIG. 4.

FIG. 5.

FIG. 1 is a top perspective view of a film cartridge showing our new design;

FIG. 2 is a top plan view thereof;

FIG. 3 is a bottom perspective view;

FIG. 4 is a left side elevational view thereof; and
FIG. 5 is an end elevational view thereof.

We claim:

The ornamental design for a film cartridge, substantially as shown.
